Primary Examiner — Justin M Jonaitis*Assistant Examiner* — Natalya M Rapundalo(74) *Attorney, Agent, or Firm* — LESLEY A. WALLERSTEIN, LLC(57) **CLAIM**

The ornamental design for a scoop, as shown and described.

DESCRIPTION

FIG. 1 is a first perspective view of a scoop, shown in a folded configuration.

FIG. 2 is a perspective view of the scoop of FIG. 1 shown in an environment of use.

FIG. 3 is a second perspective view of the scoop of FIG. 1, shown in an unfolded configuration.

FIG. 4 is a front view of FIG. 1.

FIG. 5 is a rear view thereof.

FIG. 6 is a left view thereof.

FIG. 7 is a right view thereof.

FIG. 8 is a top view thereof; and,

FIG. 9 is a bottom view thereof.

The hand and small objects drawn in broken lines in FIG. 2 are environmental structures only and form no part of the claimed design.

1 Claim, 6 Drawing Sheets(56)
